UNITED STATES PATENT OFFICE.

ROBERT H. SCHLACHTER, OF COUNCIL BLUFFS, IOWA.

DOUBLE DISK FOR GRAIN-DRILLS.

No. 800,597.

Specification of Letters Patent.

Patented Sept. 26, 1905.

Application filed May 17, 1904. Serial No. 208,482.

To all whom it may concern:

Be it known that I, ROBERT H. SCHLACHTER, a citizen of the United States, residing at Council Bluffs, in the county of Pottawattamie and State of Iowa, have invented new and useful Improvements in Double Disks for Grain-Drills, of which the following is a specification.

My invention relates to improvements in hubs and bearings for disks for grain-drills, and the objects of my invention are, first, to devise a means to properly rotate two disks touching at their edges at a suitable point to cleave the soil; second, to provide hubs for such disks that will adjust automatically for a reasonable amount of wear; third, to provide hubs having dust-proof bearings; fourth, to provide such hubs which will not gather and hold soil and refuse; fifth, to provide a cheap, simple, and efficient connection or universal joint between such hubs, carrying said disks, allowing the disks to be easily removed or disconnected. I attain these objects by a construction and device illustrated in the accompanying drawings, in which—

Figure 1 is a side elevation of the standard and hub with one disk removed. Fig. 2 is a vertical sectional view through the center of the hub of said standard and disks. Fig. 3 is a plan of said standard and disks. Fig. 4 is a side elevation of one of the said disks. Fig. 5 is a cross-section through the center of one of such disks; and Fig. 6 is a plan of the bolts b b' , having swivel-joint.

35 In the several views similar letters refer to similar parts throughout.

Upon the standard s , of any suitable shape or form for attachment, (a grain-drill and which forms no part of this invention,) a sleeve j is properly supported and internally tapered at its outer ends to form bearings for axles of hubs h and h' , extending therein, which internal bearings in said sleeves are at an angle with each other, so that the two disks d and d' touch at some definitely-arranged point of contact, as p . Upon the disks d and d' (which said disks may be made exactly alike) are secured hubs h h' , rounded or hemispherical on the outside and having an annular groove on the inside to receive the projecting end of the sleeve j at the proper depth. These hubs h and h' are tapered to form an axle which fits into and revolves in the sleeve j . The said hubs h and h' have each an axial hole through which pass the bolts b and b' , respectively. The said hubs h and h' may be coun-

tersunk on the outer or hemispherical face thereof to receive the nuts of the respective bolts b and b' , so that the extremities of the said bolts b and b' will be protected from obstacles striking the said hubs h and h' . The bolt b passes through the hole k in the hub h and is connected by any suitable universal joint, (here shown, and preferably so used, as an eyelet receiving a corresponding eyelet of another similar bolt b' ,) or the said bolt b' may be connected with the bolt b by a swivel-joint, as shown in Fig. 6, when it is desired that the disks rotate separately. The hubs h and h' may be made exactly alike, and when placed with their axles within the sleeve j are held in place by the connecting-bolts b and b' , universally jointed, so that the two disks d and d' , supported on the respective hubs h and h' , will touch at the periphery of the said disks d d' at a point p . The axles of the said hubs h and h' are made to fit the internal tapers of the respective ends of the sleeve j when the said disks d and d' touch at the point p , as aforesaid. The bolts b and b' have burs at their extremities by which the hubs h and h' , to which are fastened the disks d and d' , may be removed from the sleeve j by removing one of the burs on the connections b and b' . When it is desired that said disks do not rotate independently and bolt connections are used, the hubs h and h' may be slotted through the eyelet k at i to receive and to hold the eyelet of the bolts b b' and prevent their rotation within the hub. The hub h of the disk d may be formed as a part of the disk d or riveted or bolted thereto by rivets or bolts at r . Since the disk d , the hub h , and the bolt b are exactly similar to the disk d' and the hub h' and the bolt b' , a description of one part applies completely to the other. The bolts b b' can thus be arranged to revolve with their respective disks d and d' . When the disks attached to the standard s are drawn through the soil, the surface of which comes to the points p , a furrow or parting of the soil will be caused, whereby the grain can be dropped back of the hubs h and h' and between the disks d and d' , as in other similar disk-drills. The disks d and d' , fastened to their hubs h and h' , respectively, will revolve within and about the sleeve j , always touching at the point p . The hubs h and h' , covering the ends of the sleeve j , prevent dirt and sand from falling into the journals of the tapered axle on the said hubs h h' , within the sleeve j . The said taper on the hubs h h' is

- such that the ends of the sleeve *j* work against the bottom of the annular groove in said hubs *h h'* when the disks *d d'* touch at the point *p*. As the parts wear together, the nuts upon the bolts *b b'* may be screwed up for the proper adjustment. The outside of the hubs *h* and *h'* are made in a hemispherical or rounding shape, so that they do not gather and hold dirt and refuse.
- 10 I am aware that prior to my invention double disks have been used for grain-drills. I therefore do not claim the use of two disks for such purpose broadly; but
- What I do claim by my invention, and desire 15 to secure by Letters Patent, is--
1. The combination in a sleeved standard having internally - tapered bearings; disk-

heads with annular groove receiving said sleeve, and universal connection coupling the disks to standard. 20

2. The combination in a sleeved standard receiving tapered disk-heads at angle to each other and having annular groove or slot receiving said sleeve and a universal connection coupling disks to standard. 25

3. The combination in disk-heads having annular groove and tapered bearings, a sleeved standard and universal connection coupling disks to standard.

ROBERT H. SCHLACHTER.
